United States Patent Office

Des. 195,062

Patented Apr. 16, 1963

195,062

JUG

Lawrence C. Lynd, Pataskala, Ohio, assignor to Ohio Container Corporation, Columbus, Ohio, a corporation of Ohio

Filed May 8, 1961, Ser. No. 65,060

Term of patent 14 years

(Cl. D58—5)

FIG - 1 -

The side not shown is a mirror image of the side shown.

I claim:

The ornamental design for jug, substantially as shown, and described.
